Inventor

Frank Wicks

United States Patent Office.

FRANK WICKS, OF UPPER SANDUSKY, OHIO.

Letters Patent No. 79,284, dated June 23, 1863.

IMPROVEMENT IN HORSE-RAKES.

The Schedule referred to in these Letters Patent and making part of the same.

TO WHOM IT MAY CONCERN:

Be it known that I, FRANK WICKS, of Upper Sandusky, in the county of Wyandot, and State of Ohio, have invented certain new and useful Improvements in Hay-Gatherers; and I hereby declare that the following is a full, clear, and exact description of the same, reference being had to the accompanying drawings, and to the figures of reference marked thereon, making part of this specification, in which—

Figure 1 is a side elevation.

Figure 2, a top view.

Figure 3, a vertical section, showing the method of attaching the handles; and

Figure 4 is a section showing the method of attaching the teeth to the cross-bar.

The nature and object of my invention are to construct a hay-gatherer, simple in form and construction, and easy and practical in its operation.

To enable others skilled in the art to make and use my invention, I will proceed to describe its construction and operation.

Similar letters of reference refer to the same parts in the different drawings.

E is a runner, of which there are two.

D D are the runner-rails.

A is the tongue.

G is a post, extending from the runner to the rail, and located at or near the point where the runner begins to turn upward. It is also located back of the front point of the teeth, making the front end of the teeth come in advance of the posts as the machine is drawn over the ground.

F is an iron shoe, placed on the bottom of the runner, at the point where it begins to turn upwards, and extending a sufficient distance each way to accomplish the object desired, which is to prevent the wearing of the runner at this point as it is drawn over the ground.

I is a cross-bar, extending from the heel of one runner to the other. To this cross-bar, I, are attached the teeth P P.

b b is a cross-bar from the front end of one runner to the front end of the other, and to which is attached the tongue A.

d d are braces, extending from the tongue to the cross-bar b b.

k k are the handles, attached to the cross-bar I, to which they are attached by means of two straps of iron, one of which extends from the upper side, and the other from the lower side of the handle. Around the cross-bar I, near one end of the strip of iron passing over the upper side of the handle, is a hole, through which the lower end of the other strip of iron passes, and terminates in a screw, on which is placed a nut, as shown at a, fig. 3. The handles k k are cut so as to fit two sides of the cross-bar I, as shown at fig. 3.

S S S are cross-rounds, extending from one handle to the other.

O and N are iron braces, fastened to the cross-bar I, and extending to the handles k k, they pass through the handles k k. On the end passing through the handles is a screw, on which is placed a nut, t.

The cross-bar b b is fastened to the front end of the runners by making a half-socket in the front ends of the rails D D, in which are placed the ends of the cross-bar, and over each end is placed an iron cap; this cap is then fastened to the rail by means of bolts and nuts.

The operation of this invention is as follows: The team is attached to the tongue A, which draws the gatherer over the ground, and the teeth gather the hay, and when sufficient is gathered, the operator, having hold of the upper round S, lifts up the heel of the gatherer a little; this act catches the points of the teeth in the ground, when the system of teeth and handles is turned over, and thus the gathered hay is deposited. The teeth and handles are brought back to their proper position by the dogs T on the handles (fig. 3) catching in the ground and again turning them over.

By placing the post G back of the front end of the teeth, the bend of the runner is carried back of the

front end of the teeth, the heel of the gatherer is caused to be slightly elevated, sufficiently to permit the front ends of the teeth to hug the ground by the act of drawing the gatherer over the ground, thus gathering all the hay, and relieving the operator of the necessity of lifting by main strength the heel of the gatherer to accomplish this same result.

By fastening the handles to the cross-bar I in the manner described, I am able to keep the handles snugly fitted to the cross-bar, by tightening the cross-nut a.

By fastening the ends of the braces O and N to the handles by means of a nut and a screw, I can always keep the handles in proper position by tightening up the nuts.

By using the caps C C over the ends of the cross-bar b b, in fastening it to the rails D D, I am enabled to use a much smaller rail than I otherwise could. The joints at the ends of the two cross-bars are made flexible, so as to allow the runners to conform to the inequalities of the surface.

Having thus described my invention, what I claim as new, and desire to secure by Letters Patent, is—

1. The runners E E, constructed substantially as described, with the curved part extending from the front extremity to the rear of the line of the points of the teeth P P, for the purpose set forth.

2. Locating the post G, or its equivalent, back of the points of the teeth P P, substantially in the manner and for the purpose specified.

3. The construction and arrangement of the rods or braces N O, with the handles and cross-bar I, and nuts t t, for the purpose of bracing the handles to the cross-bar I, substantially in the manner described.

FRANK WICKS.
